UNITED STATES PATENT OFFICE

92,647

DESIGN FOR A BOTTLE OR SIMILAR ARTICLE

William John du Bree, Greenwich, Conn.

Application April 11, 1934, Serial No. 51,375

Term of patent 14 years

To all whom it may concern:

Be it known that I, WILLIAM JOHN DU BREE, a citizen of the United States, residing in Greenwich, Fairfield County, Connecticut, have invented a new, original, and ornamental Design for a Bottle or Similar Article, of which the following is a specification, reference being had to the accompanying drawing, forming part thereof.

I claim:

The ornamental design for a bottle or similar article as shown.

WILLIAM JOHN DU BREE.
